UNITED STATES PATENT OFFICE.

NICOL MACNICOL, OF KAMLOOPS, BRITISH COLUMBIA, CANADA.

HOLDER FOR MEMORANDUM PADS.

Application filed June 6, 1923. Serial No. 643,760.

To all whom it may concern:

Be it known that I, NICOL MACNICOL, a subject of the King of Great Britain, and a resident of the city of Kamloops, in the 5 Province of British Columbia, Canada, have invented certain new and useful Improvements in Holders for Memorandum Pads, of which the following is a specification.

My invention relates to improvements in 10 holders for memorandum pads the objects of which are to provide a holder for loose leaf calendars or pads for desk use, in which both sides of such leaves may be conveniently used for notes, whereby great economy 15 of papers is effected and a more comprehensive record thereof may be kept, a further object of the invention is to so dispose the used leaves of the pad that they are not in the way of the writer's hand 20 as is common with pads bound or fastened along one of their sides.

My invention consists essentially of a panel having opposing slopes and means thereon for holding a loose leaf pad by its 25 upper margin that each page as it is used may be turned over to lie upon the opposing slope of the panel, as will be more fully described in the following specification, in which:—

- 30 Fig. 1 is a plan view of my invention.
Fig. 2 is a side view.
Fig. 3 is a view taken from one end.
Fig. 4 is a section showing the staple carrying wedge.

35 In the drawings like characters of reference indicate corresponding parts in each figure.

The numeral 1 indicates generally the base panel of my holder which is preferably arched on the underside as at 2, 40 to reduce its weight, and which is provided at opposite ends with narrow strips of rubber or other suitable material 3 upon which the panel 1 rests.

45 The numerals 4 and 5 indicate opposing slopes extending inwards and upwards from the ends of the panel, upon which the calendar or pad is adapted to rest, 6 is a horizontal portion of the panel connecting the 50 upper ends of the slopes 4 and 5 together,

which is provided with an undercut wedge shaped groove 7 lengthwise thereof. 8 indicates a wedge removably held in the groove 7 and surmounted by a pair of staples 9, one leg of each of which is 55 threaded as at 10 and provided with a nut 11 by which the staples are secured to the wedge.

The numeral 12 indicates a loose leaf pad having perforations 13 along its upper edge through which the pad is bound to the panel by the staples 9. 14 indicates a grooved strip secured to one side of the base panel 1 to form a pencil holder for the device. 65

Having thus described the several parts of my invention I will now briefly describe its use.

The loose leaf pad is first set in position on slope 5 of the base panel with 70 the binding staples 9 inserted through the apertures 12. As the front of each leaf of the pad is used it is lifted over the bow of the staples and allowed to come to rest upon slope 4 with its reverse (unused) side 75 now uppermost, the pad is then turned around when the reverse side of the leaf is in position to be used for writing further notes.

When it is desired to change from one 80 pad to another, the wedge 8 is withdrawn from the panel and the staples detached therefrom, when one pad may be removed and another put in its place and the device re-assembled. 85

From the foregoing it will be seen that I have invented simple holders for memorandum pads which permits the use of both sides of each leaf thereof, and in which no obstruction or inconvenience is offered 90 to the hand of the writer by the accumulated stack of leaves on the opposite side of the binding staples or from the binding staples themselves.

What I claim as my invention is:

A holder for memorandum pads comprising a base having a concave under surface and a convex upper surface whereby the intermediate portion of the base is elevated with respect to the end portions, 100

said intermediate portion being provided in its upper surface with a cross groove gradually decreasing in width at one end and having under cut side walls, a removable strip having a shape complementary to said groove and wedged therein and pad binding means carried by said strip.

Dated at Kamloops, British Columbia,
this 1st day of May 1923.

NICOL MACNICAL.
